UNITED STATES PATENT OFFICE.

HENRY D. JAMES, OF PITTSBURG, PENNSYLVANIA, ASSIGNOR TO WESTINGHOUSE ELECTRIC & MANUFACTURING COMPANY, A CORPORATION OF PENNSYLVANIA.

RESISTANCE-TERMINAL.

No. 851,667.

Specification of Letters Patent.

Patented April 30, 1907.

Application filed May 16, 1906. Serial No. 317,230.

To all whom it may concern:

Be it known that I, HENRY D. JAMES, a citizen of the United States, and a resident of Pittsburgh, in the county of Allegheny and State of Pennsylvania, have invented a new and useful Improvement in Resistance-Terminals, of which the following is a specification.

My invention relates to terminal members for electrical apparatus and it has for its object to provide a terminal that shall be simple and durable in construction and especially adapted for use with groups of assembled resistance units.

A well known form of resistance for use with electric circuits is illustrated and described in Patent No. 788,686, granted May 2, 1905, to Westinghouse Electric & Manufacturing Company, as assignee of Hermon L. Van Valkenburg. This resistance comprises a plurality of bars of iron or other suitable material, which are supported by independent insulating blocks having recesses in which the ends of the bars are seated and suitable resistance conductors which are coiled about the rods and are separated therefrom by a wrapping of insulating material. Resistances of this character are often assembled in layers and it is sometimes desirable to provide suitable terminal members which are connected to intermediate points in the resistance group.

According to my present invention, I provide complementary slots in the adjacent walls of the independent insulating blocks which form passages through which terminal members may pass and in which such members may be supported.

My invention is illustrated in the accompanying drawings, in which

Figure 1 is a plan view, and Fig. 2 an elevation of a portion of a resistance group provided with the terminal members of my invention. Fig. 3 is a sectional elevation along the line III—III of Fig. 1.

Referring to the drawings, the resistance group illustrated comprises a plurality of bars 1, having suitable wrappings of insulating material upon which are wound resistance conductors 2, and also a supporting frame 3, insulating blocks 4, and a plurality of terminal members 5. The insulating

blocks 4 are supported in channels provided in opposite sides of the frame 3, and their adjacent sides are provided with complementary recesses, or notches 6, which form passages through which the terminal members 5 may project.

The terminal members 5 are of strap form and each of them is given a short offset bend at each end of the passage between the insulating blocks, in order that the members may be securely held in position. The inner ends of the terminal members are provided with projections 7, about which the ends of the resistance conductors may be wound, or to which they may be otherwise electrically connected and their outer ends are bent substantially at right angles to their body portions. The bent portions, as illustrated in the drawings, are drilled to receive screws by means of which conductors may be detachably connected thereto.

Numerous other well known devices may be employed, within the scope of my invention, for electrically connecting any desired conductors with the terminal members.

I claim as my invention:

1. The combination with a frame and a plurality of resistance elements each comprising a rod or bar, a sheet or covering of insulating material and a resistance coil surrounding said sheet or covering, of independent insulating blocks having recesses in which the ends of said bars are seated and notches in their adjacent walls, and terminal members which project through and are supported in the passages formed by said notches.

2. The combination with resistance units and a frame in which the units are assembled, of insulating supporting blocks having complementary notches in their adjacent sides, and terminal members that project through and are supported in the passages which are formed between the insulating blocks by the complementary notches.

3. A terminal member for electrical apparatus that comprises a body portion, an end projection in the same plane, a bent portion at the opposite end and a binding screw in the bent portion.

4. A resistance group comprising a supporting frame having opposite channels, resistance units and insulating end supporting

blocks therefor that are assembled in the channels, and terminal members which project through passages formed in and between the insulating blocks.

- 5 5. The combination with a frame and a plurality of resistance elements each comprising a rod or bar, a sheet or covering of insulating material, a resistance coil surrounding said sheet or covering, independent insulating blocks having recesses in which the ends of said bars are seated, and terminal pieces each of which comprise a body portion, an end projection in the same plane, a bent portion at the opposite end and a binding screw in the bent portion.
- 10 6. The combination with resistance units, a frame in which the units are assembled, and insulating end-supporting blocks having complementary notches in their adjacent sides, of terminal members each of which comprises a body portion, an end projection in the same plane, a bent portion at the oppo-

site end and a binding screw in the bent portion.

7. In a resistance group, a set of resistance elements, a set of supporting blocks having narrow passages formed in and between them and terminal strips projecting through said passages and having offset bends at the ends of the passages and laterally projecting end portions in different planes.

8. A strap terminal member having a lateral projection at one end in the plane of its body portion, a lateral projection at its other end at right angles to the plane of the body portion and intermediate offset bends.

In testimony whereof, I have hereunto subscribed my name this 10th day of May, 1906.

HENRY D. JAMES.
